UNITED STATES PATENT OFFICE.

HENRY P. ROBERTS, OF BOSTON, MASSACHUSETTS, ASSIGNOR, BY MESNE ASSIGNMENTS, TO ALBERT A. ORMSBEE, CHARLES S. McCALL, AND GEORGE GREENE, ALL OF TAUNTON, MASSACHUSETTS.

INTERCHANGEABLE RESILIENT HEEL.

1,075,303.

Specification of Letters Patent.

Patented Oct. 7, 1913.

Application filed November 13, 1912. Serial No. 731,212.

To all whom it may concern:

Be it known that I, HENRY P. ROBERTS, of Boston, in the county of Suffolk and State of Massachusetts, have invented certain new and useful Improvements in Interchangeable Resilient Heels, of which the following is a specification.

This invention relates to interchangeable resilient heels.

10 The object of the invention is to provide a resilient or rubber heel which may be readily detached from the heel of a shoe and replaced on another, whereby a pair of heels are interchangeable so that they may 15 be worn evenly, thereby lengthening their life and increasing their comfort to the wearer.

I will describe my invention in the following specification and will point out the 20 novel features thereof in the appended claim.

In the accompanying drawing, Figure 1 is a sectional side elevation showing a rubber heel attached to the heel of a shoe with 25 one embodiment of my invention, Fig. 2 is a fragmentary plan view of the same, Fig. 3 is a perspective view of the stationary member of the attaching device, Fig. 4 is a perspective view of the removable member of the attaching device, Fig. 5 is a fragmentary plan view of a heel secured in 30 place by a modified form of the invention, and Fig. 6 is a perspective view of the stationary member of this modified form.

35 As illustrated in Figs. 1 to 4, inclusive, a removable heel 10, preferably of rubber, is secured to the leather heel 12. This is accomplished by a pair of interengaging members 14 and 16, which are detachably connected. The member 14 comprises a sheet metal plate having a series of nail holes 18, and provided with a plurality of upwardly extending ears or projections 20, each provided with apertures 22, preferably rectangular. The member 14 is preferably sunk into the outer lift of the heel of the shoe so that the lower face of the plate 14 is flush with the lower face of said lift. This member is preferably secured in place by 45 50 nails passing through the holes 18 therein.

The heel 10 is provided with recesses which are adapted to receive the ears 20, and also with a series of passages extending longitudinally in alignment with the aper-

tures 22 and communicating with said recesses. These passages are adapted to receive prongs 24, 25 and 26 of the removable securing member 16. These prongs are connected to a bar or plate 28 extending at right angles to the plane of the prongs 60 and is adapted to lie against the breast of the heel 12 when the resilient heel 10 is secured in place on the shoe. If desired, the plate 28 may be secured in place to prevent the securing member from working out under the action of the wearer while walking, it being understood that the prongs 24, 25 and 26 frictionally engage the walls of the 65 70 75 passages in the rubber heel.

As illustrated in Figs. 5 and 6 a stationary member 30 is provided, having offset ears 32 and an overturned ear 34. This member is affixed to the heel as described above, and the ears 32, 34 are received in correspondingly located recesses in the rubber heel 40, and this heel is provided with longitudinally extending passages which are 80 85 90 95 100 105 adapted to receive the prongs of the member 16.

It will be noted that the ears or projections on the stationary or fixed members are symmetrically located so that they will enter either heel of a pair; and it is merely necessary to insert the prongs 24, 25 and 26 into the heel to engage said ears to hold the rubber heel in place. The prongs are arranged to fit the passages in the heel tightly to prevent accidental removal of the prongs therefrom.

By reference to the drawing it will be observed that one of the projections 20 and the projection 34 are located on the longitudinal median line of their plate, and in addition there are two pairs of projections, one pair on each edge of the plate, one projection being on each corner thereof. The securing member comprises three prongs, the central prong being arranged for engagement with the single central projection, and the side prongs being each arranged for engagement with the corresponding pair of projections on the plate which is affixed to the outer lift of the heel.

While I have illustrated and described a preferred embodiment of the invention, I am aware that many modifications can be made therein by any person skilled in the art without departing from the scope of the

invention as expressed in the claim. Therefore I do not wish to be limited to all the details of construction shown and described, but

5. What I claim is:

The combination of a plate adapted to be affixed to the heel of a shoe, said plate being substantially rectangular, of substantial area, and having an extension in the direction of the longitudinal median line of the shoe and toward the rear of the heel, each corner of said plate and the end of said extension having an ear, a resilient heel arranged to fit said shoe heel and provided 15 with a series of recesses arranged to receive

said ears, said resilient heel being also provided with a plurality of parallel passages communicating with said recesses, and a removable member having a plurality of prongs arranged to enter and completely 20 fill the passages in said resilient heel and to frictionally engage the walls of said passages, said ears being also arranged to engage said prongs, substantially as described.

In testimony whereof I have affixed my 25 signature, in presence of two witnesses.

HENRY P. ROBERTS.
